(57) **CLAIM**

The ornamental design for a breaker of tile cutter as shown and described.

DESCRIPTION

FIG. 1 is a top side perspective view of a first embodiment of a breaker of tile cutter showing my new design;

FIG. 2 is a bottom side perspective view as shown in FIG. 1;

FIG. 3 is a front elevational view as shown in FIG. 1;

FIG. 4 is a rear elevational view as shown in FIG. 1;

FIG. 5 is a left side elevational view as shown in FIG. 1;

FIG. 6 is a right side elevational view as shown in FIG. 1;

FIG. 7 is a top plan view as shown in FIG. 1;

FIG. 8 is a bottom plan view as shown in FIG. 1;

FIG. 9 is a top side perspective view of a second embodiment of a breaker of tile cutter showing my new design;

FIG. 10 is a bottom side perspective view as shown in FIG. 9;

FIG. 11 is a front elevational view as shown in FIG. 9;

FIG. 12 is a rear elevational view as shown in FIG. 9;

FIG. 13 is a left side elevational view as shown in FIG. 9;

FIG. 14 is a right side elevational view as shown in FIG. 9;

FIG. 15 is a top plan view as shown in FIG. 9; and,

FIG. 16 is a bottom plan view as shown in FIG. 9.

The broken lines shown in the drawings are for illustrative purposes only and form no part of the claimed design.

1 Claim, 16 Drawing Sheets
